UNITED STATES PATENT OFFICE.

HENRY F. POPE, OF CLEVELAND, OHIO, ASSIGNOR TO THE NATIONAL MALLEABLE CASTINGS COMPANY, OF CLEVELAND, OHIO, A CORPORATION OF OHIO.

UNCOUPLING MECHANISM FOR CARS.

No. 834,321.

Specification of Letters Patent.

Patented Oct. 30, 1906.

Application filed April 8, 1905. Serial No. 254,438.

To all whom it may concern:

Be it known that I, HENRY F. POPE, of Cleveland, Cuyahoga county, Ohio, have invented a new and useful Uncoupling Mechanism for Cars, of which the following is a full, clear, and exact description, reference being had to the accompanying drawings, forming part of this specification, in which—

Figure 1 is a plan view of the end portion 10 of a car-frame constructed in accordance with my invention. Fig. 2 is a side elevation. Fig. 3 is a front elevation. Figs. 4 and 5 are detail views.

The purpose of my invention is to provide 15 a coupler-operating device especially adapted for use with cars equipped with radially-movable draft-riggings, such as are described in the patent granted to H. T. Krakau, re-issue No. 12,275, dated October 18, 1904. 20 It provides mechanism in which the operating-rods are independent of the coupler and will permit the coupler and draft-rigging to have not only the ordinary longitudinal movement incident to buffing and draft, but 25 also a wide range of lateral motion. The operating-lever will operate the coupler-lock irrespective of the lateral position of the coupler-head.

The drawings represent the preferable construction 30 of my invention; but it may be modified in many ways by the skilled mechanician.

3 represents the end sill of the car.

4 is the coupler-head connected to a radially-movable draft-rigging, and 5 is the usual chain by which the lock of the coupler is operated.

6 is a bracket projecting upwardly from the upper side of the frame 7, which carries 40 the coupler and draft-rigging. This bracket is preferably situate just back of the end sill and may be riveted to or cast integral with the frame 7. It furnishes the pivotal support for the end of the lock-lifting lever 8, to 45 the forward end of which the chain 5 is attached, and this lever being connected with the coupler and draft-rigging moves laterally with them in their radial motion.

The crank-shaft 9, by which the lever 8 is 50 operated, is preferably a double rod made in a single piece extending from side to side of the car and is provided at the ends with de-

pending handles 10 10. This shaft is journaled in bearings 11 on the end sill or other convenient place and at its middle has a 55 crank portion 9', which projects forwardly and extends under the lever 8. Instead of a double rod a single rod may be used extending from one side of the car and terminating at the far end of the crank 9'. 60

The lever is preferably provided with a downwardly-projecting foot 12, which rests on top of the end sill and upholds the lever at its forward end, and for the purpose of preventing the lever from obstructing the front 65 of the car and to enable the brakeman to walk over the end sill without being tripped by the lever I prefer to box it in or cover it with a shield 13, which may be made of pressed steel and is attached to the end sill or 70 car-frame.

When the parts are thus constructed, the lever 8 will move laterally with the draft-rigging and coupler in the radial motions of the latter; but notwithstanding the extent of 75 such motion the lever will always be directly above the crank 9', which is of sufficient length for that purpose, so that at any time by raising the handle 10, and thus lifting the crank 9', the lever may be elevated to operate the coupler-lock. If the coupler or its attachments should break in such a way as to allow the coupler to pull out to an unusual extent, the lever will automatically unlock the coupler and will hold it up from the 80 track.

I claim—

1. In a car-coupler, the combination with a draw-head normally capable of lateral movement and provided with a coupling-jaw, and a coupling-lock therefor, of a transversely-extending operating-lever, having a crank portion extending over the draw-head, a pivoted lever having a free arm extending across and overlying the said crank portion, 95 and a connection between said lever and the coupling-lock; substantially as described.

2. In a car-coupling, the combination with a draw-head normally capable of lateral movement and provided with a coupling-jaw and locking means therefor, of a transversely-extending shaft having a broad crank portion extending over the draw-head, 100 and a pivoted lever having a free arm ex-

tending across and resting upon said crank portion and connected to said locking means; substantially as described.

3. In a car-coupling, the combination with
5 a draw-head normally capable of lateral
movement and provided with a coupling-
jaw and locking means therefor, of a trans-
versely-extending shaft having a broad
crank portion extending over the draw-head,
10 and a pivoted lever having a free arm resting

upon said crank portion, and a flexible mem-
ber connecting said lever with the locking
means; substantially as described.

In testimony whereof I have hereunto set
my hand.

HENRY F. POPE.
